Primary Examiner — Robert M Spear*Assistant Examiner* — Darcey E Heflin(74) *Attorney, Agent, or Firm* — Harness, Dickey & Pierce, LLP(57) **CLAIM**

The ornamental design for a display package, as shown and described.

DESCRIPTION

FIG. 1 is a perspective view of a display package showing our new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken line showing is for environmental purposes only and forms no part of the claimed design.

1 Claim, 4 Drawing Sheets(56)
